Primary Examiner — Garth Rademaker*Assistant Examiner* — Katie Stofko Mroczka(74) Attorney, Agent, or Firm — Morrison & Foerster, LLP(57) CLAIM

We claim the ornamental design for an edible cup, as shown and described.

DESCRIPTION

FIG. 1 is a top view of the edible cup.

FIG. 2 is a side view thereof.

FIG. 3 is a bottom view thereof; and,

FIG. 4 is a perspective view thereof.

The inside of the edible cup and the broken lines shown in FIGS. 1, 3 and 4 illustrate portions of the edible cup that form no part of the claimed design.
